MARVIN W. DITTO, OF NEW YORK, N. Y.

APPARATUS FOR SEPARATING COAL.

Application filed June 2, 1922. Serial No. 565,381.

My invention relates to a novel means for separating coal from its impurities.

While the invention herein is described specifically as relating to the separation of coal from its impurities, it is to be understood that the invention is not limited to coal nor any other specific material but may be applied to grading, separating or classifying of any desired material.

10 In the matter of preparing coke for metallurgical and other purposes, it is desirable to exclude as much of the impurities such as slate, earthy material and the like as is possible. Primarily a good grade of coal is employed and this is freed as largely as possible from the large pieces of slate and earthy material which can conveniently be picked out. This leaves the smaller particles of impurities and also leaves such impurities as are left clinging to lumps of coal. The coal is then ground or crushed to a fineness capable of passing a $\frac{1}{8}$ -inch mesh screen. The crushing of the coal releases many of the smaller particles of slate and 25 the like which adhered to the lumps of coal, and it is then possible to remove a large portion of the impurities.

I am aware that the broad result of separating out one constituent of a mass from another or others is old, but heretofore, such separation particularly in the case of coal, has been secured only at the expenditure of a relatively great amount of power and consequent expense, or at some equally serious disadvantage.

My invention aims broadly to provide an improved apparatus for separation of coal and other materials to be graded or separated.

40 The particular manner in which I accomplish this is through the use of a reciprocating table with either a plane or a riffle top which is activated or sensitized by vertical vibrations of relatively high frequency.

In order to acquaint those skilled in the art with the manner of constructing, operating and practicing my invention, I shall now describe in connection with the accompanying drawings a specific embodiment of the invention. In the accompanying drawings Figure 1 is a diagrammatic plan view of a separating table employing my invention;

55 Fig. 2 is a further diagrammatic illus-

tration indicating more particularly the manner of use of the same;

Fig. 3 is a section taken on the line of 3-3 of Fig. 2, and

Fig. 4 is an isometric view of a modified device embodying my invention.

Figure 1 shows diagrammatically the top of a table or riffle suitable for practicing my invention. The table top A B C D provides a plane surface which may in practice be of suitable dimensions such as 6 feet wide by 12 feet long, resting upon casters or swinging links as is well understood in the art, and moved longitudinally by an eccentric head motion which is indicated at 5 for imparting to the table a back and forward movement within adjustable limits as indicated by the arrows 6, 7.

The table is so mounted that it may be adjustably inclined in two directions as indicated in Figure 1 by the arrows 8 and 9. Preferably the point C, which is the lower right hand corner in the figure, has the maximum depression below a horizontal plane, point B being higher than C and 20 point D being higher than point B and point A being uppermost.

Broadly speaking, so much of the arrangement as I have described, is known in the art and has been employed generally with water running over the table to separate metal from earthy matter or gangue in recovering metallic values from ores, or in connection with other processes.

90 In the separation of coal from its impurities, assume that we place two particles, namely, a heavier particle 1 of slate or earthy material, and a lighter particle 2 of coal upon the table side by side as shown, and impart to the table the reciprocating motion from the eccentric head mechanism 5. Assuming that the particle 2 were not in the way, the particle 1, would in a series of small excursions as indicated by the scalloped line 3, move partly longitudinally 95 and partly transversely off the table along the line 1-11.

Assuming that the particle 2 were alone on the table and it was subjected to the motion of the table, it would tend to follow 105 the path indicated by the scalloped line 4 along the path 2-12. However, in practice, it is necessary to treat as much material as can possibly be handled on the table at the same time, and a very much aggravated 110

condition over that shown in Figure 1 is the result. As shown in Figure 1, the path of movement of the particle 1 intersects that of the path of movement of the particle 2 with the result that the particle 1 would tend to push the particle 2 ahead of it in the general direction 1-11 instead of permitting it to proceed along the general direction 2-12. It is necessary, therefore, to let the particle 1 pass the particle 2 with great freedom, otherwise the separating tendency will be ineffective on account of interference. Where water is employed, the lifting and lubricating property of the water permits the particles to pass each other with relatively great freedom. However, in the matter of separating coal from its impurities it is undesirable to employ water since water is difficult to remove from the coal except by direct evaporation, and this involves a distinct loss in power, takes time and attention and makes the matter of coking more difficult.

The essence of my invention is to activate these particles, as they move across the table, by a motion of vibration. In other words, I vibrate the table top vigorously at a high frequency so that the particles dance up and down and thereby have great freedom of motion with respect to each other, both with respect to vertical movement to permit the heavier particles to sink to the bottom of the layer of material, and also great freedom in a lateral direction to permit the heavier particles to travel longitudinally of the table at a greater rate than the lighter coal particles.

The invention may appear in a great variety of apparatus and the fundamental idea of activating or enlivening the layer of material may, if desired, be assisted by other means such for instance as the use of liquids or fluids tending to levitate the particles on the table top. This action of vertical vibration in connection with horizontal riffling permits of a great increase in capacity with a consequent saving in power.

As shown in Figures 2 and 3, the table is divided into three sections, 13, 14 and 15, this table comprising a suitable framework, comprising the back 16 and the sides 17 and 18 and suitable ends with division walls or partitions 21 and 22 with a metallic sheet in one or more sections stretched across the frame to form the table top 23. This table top is of suitable sheet material capable of withstanding tension sufficient to make it vibratile in character. This top 23 thus becomes a member which may be readily vibrated like the head of a drum. I provide means such as the rapping device shown at 24 for vibrating the particular section of the head or top 23. In this case a number of links or arms 25 are pivoted loosely upon pins 26, these arms or links being slotted

and being adapted to be thrown outwardly by centrifugal force as the central member or disc 27 is rotated. These arms or links are adapted to strike a wear plate 28 secured upon the bottom of the corresponding head section. These links or arms 25 are adjustably positioned with respect to the plate 28 so as to be capable of varying the amplitude of vibration of the corresponding diaphragm or head member, and the speed of rotation 70 of the shaft driving these arms may be varied to vary the frequency or pitch of vibration. Preferably the size and tension of the diaphragm is adjusted to correspond to the pitch of vibration of the striking or rapping 80 arms 25.

In the adjacent compartment I have shown an electrically operated vibrating mechanism comprising the solenoid winding 28' which is connected to a suitable source 85 of current as shown at 29, this source of current being preferably of such a character as to provide a suitable alternating current of the desired frequency. A solenoid core 30 is adapted to strike the wear plate 90 31 fastened upon the bottom of the corresponding section of the head 23. This solenoid core is moved in one direction by the attraction of the solenoid winding 28 and is moved in the opposite direction preferably by an adjustable spring such as shown at 32, this spring being placed under the desired tension by an adjustable compression screw 33. In accordance with the construction herein shown, impulses of current may 100 be employed.

In the third compartment I have illustrated a magnet structure 34 comprising the U-shaped core 35 and the armature 36 which co-operates therewith as being secured to the frame 16 and the head or diaphragm 23 respectively, a winding 37 being provided for one limb of the core and an interrupter 38 being connected in series with the core and a source 39 of direct current. 105

I do not intend to be limited to any particular type of vibrating mechanism, as any means which provides a suitable vibrating or hammering action upon the diaphragm or head member may be employed so long as it performs the function of activating or vibrating the material upon the top of the table. It is not essential that the various parts of the table top be vibrated all to the same amplitude nor to the same frequency so long as the desired result above indicated is obtained. I wish to point out, furthermore, that more than one actuating mechanism may be employed, and that the combined frequency of the two may act 110 upon the material if desired.

As shown in Figure 2 a feed box is provided at 40 for feeding the material upon the table top at the upper left hand corner 115 of the same. This top is provided with the 120

adjustable riffles or ribs 41 which extend preferably longitudinally of the table. The feed box is designed to provide a uniform flow of pulverized or ground coal onto the head of the table whereupon the material comes into violent agitation and simultaneously is operated upon by the reciprocating action of the table whereby the heavier material, namely the slate, sand and other 10 impurities are sifted through the coal, which is lighter, the heavier particles traveling in contact with the table top longitudinally of the riffles and being discharged off the end of the table as indicated at 42 15 between the guiding walls therein shown. The lighter material, namely, the coal, which has been displaced to the top of the table rolls more freely down the lateral inclination, being less affected by the longitudinal reciprocation of the table. Due to the vibratory action of the table in maintaining a very free flow of the heavier particles down towards the table top, and an upward flow of the lighter particles above 20 the same, a high speed of treatment and a very satisfactory degree of separation is attainable. The particles of coal are discharged off of the lower lateral edge of the table between the walls or vanes 43. 25

This separation may be made while the material is completely dry, but it does not preclude the use of a fluid medium for assisting in the separation. Water is generally undesirable since it must be evaporated off and this takes a great deal of heat which does no particular good. I may, however, assist in activating the material by the use of air, this air being driven up through the table top itself, which table top is provided 30 with suitable openings for permitting the same.

In Figure 4 I have shown a table top of this construction, in which, in addition to the vibrating mechanism for vibrating the table top in a direction substantially at right angles to the plane of the top, I provide also fluid lubricating means (in this case, air) which is fed into the various compartments 13, 14 and 15 through the openings 44, 45 and 46, the head of the table, that is, the diaphragm or top in this case being made of a foraminous sheet placed under suitable tension so as to be easily vibrated by means such as I have previously described. In this case the air which is forced through the foraminous table top assists in the segregation of the two types of particles by a tendency to levitate the

particles above the vibrating top or head. The top or head in this case may be made of a fine mesh screen or other suitable fabric providing closely spaced holes through which the air may be discharged in minute streams through the material. The supply of air which is required under this mode of operation is far less than that which would be required to lubricate the particles past each other if no mechanical vibration of the table top were provided. That is to say, a very great velocity would be necessary to lift the particles whereas according to my improved method of operation the particles are lifted by repeated contact with the vibrating surface, the air in this case merely assisting in holding the particles suspended above the vibrating top by increasing the amplitude of vibration of these particles. It will be appreciated at once that the particles are driven upwardly by the vibrating surface, and that they are assisted in their upward travel by the current of air which also retards their return to the table top whereby a greater amplitude of vibration and a consequent greater freedom of the particles with respect to each other is secured. The combined effect of mechanical vibration and fluid flotation provides a method of operation which is a great advance over the previous devices with which I am familiar.

In interpreting the frequency, it is desirable to take into account the critical point for the material under treatment. The range may lie between zero and sixty-thousand vibrations per minute.

I do not intend to be limited to the details shown or described.

I claim:

In combination, a table, said table having a flexible diaphragm-like top normally under tension, and permeable to the flotation fluid, but impermeable to any of the material treated, said table being inclined in two directions with the corners successively one higher than the other and vice versa with the corners successively lower than the other, means for simultaneously and independently vibrating areas of said table top vertically at the same and different amplitudes and frequencies, means for reciprocating the table substantially horizontally at a lower frequency, and means for causing an upward fluid flotation supply through the table top.

In witness whereof, I hereunto subscribe my name this 31st day of May, 1922.

MARVIN W. DITTO.
